CLAIM

The ornamental design for an automobile steering wheel, as shown and described.

DESCRIPTION

FIG. 1 is a front perspective view of an automobile steering wheel.

FIG. 2 is a back perspective view thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a left elevation view thereof; and

FIG. 8 is a right elevation view thereof.

FIG. 9 is a front perspective view of the automobile steering wheel rotated counterclockwise while the display remains vertically aligned; and,

FIG. 10 is a front perspective view of the automobile steering wheel rotated clockwise while the display remains vertically aligned.

The broken line showing portions of the automobile steering wheel, as well as directional arrows, are provided for the purposes of illustrating environmental structure and form no part of the claimed design.

1 Claim, 8 Drawing Sheets
